UNITED STATES PATENT OFFICE.

ROBERT J. SMIRLE, OF SAN FRANCISCO, CALIFORNIA.

WIRE-BINDING MACHINE.

1,325,916.

Specification of Letters Patent. Patented Dec. 23, 1919.

Application filed January 7, 1918. Serial No. 310,607.

To all whom it may concern:

Be it known that I, ROBERT J. SMIRLE, a citizen of Canada, and a resident of the city and county of San Francisco, State of California, have invented a certain new and useful Wire-Binding Machine, of which the following is a specification.

The invention relates to machines for wire binding boxes, bunches of shooks, etc.

10 An object of the invention is to provide a machine for passing a wire around a box or bunch of shooks, drawing the wire tight and twisting the ends of the wire.

Another object of the invention is to provide a machine which automatically accomplishes the operations of passing the wire around the bundle, drawing it tight, twisting the ends, and cutting the wire.

Another object of the invention is to provide means for alining and compressing the bunch of shooks before they are bound together.

A further object of the invention is to provide an improved mechanism for forming the wire into a loop.

The invention possesses other advantageous features, some of which, with the foregoing, will be set forth at length in the following description, where I shall outline in full, that form of the invention which I have selected for illustration in the drawings accompanying and forming part of the present specification. In said drawings I have shown one specific form of my generic invention, but it is to be understood that I do not limit myself to such form, since the invention as expressed in the claims may be embodied in a plurality of forms.

Referring to said drawings:

40 Figure 1 is a side elevation of the machine of my invention, parts thereof being broken away and parts being shown in section.

Fig. 2 is a front elevation of the machine, parts thereof being broken away.

45 Fig. 3 is a plan view of the driving mechanism dissociated from the machine.

Fig. 4 is a rear elevation of a portion of the driving mechanism.

50 Fig. 5 is a section of the wire-carrying shuttle.

Fig. 6 is a rear elevation of the wire holding, twisting and cutting head in cutting position.

Fig. 7 is a similar view of the head in wire-gripping position.

55

Fig. 8 is a section through the head.

Fig. 9 is a rear elevation partly in section of the head carrying frame.

The function of the machine is to pass a wire or metallic strip around a box, or a 60 bunch of shooks, or a similar object, draw the wire tight so that the box or bunch of shooks is bound, twist the ends of the wire and cut the wire adjacent the twisted portion. The machine comprises a suitable 65 frame 2 upon which the various mechanisms which coöperate to produce the desired result are mounted. The frame is provided with extended portions 3 which form tables or supports for the box or bundle of shooks, 70 and with an extension 4 overlying the bunch of shooks 5. The upper portion of the frame is formed of two parts spaced apart laterally from each other, so that a passage is formed for the free movement of 75

the wire-carrying shuttle. Mounted on each frame part are a plurality of sprockets 6, 7, 8, 9, 12, 13, the sprockets of each pair being axially alined, and engaging each group of sprockets is an endless chain 14, there being two parallel spaced chains. The sprockets 8—9 are carried on an adjustable cross-head 15, so that the tension of the chain may be adjusted when desired. Connecting the two chains and preferably rotatably mounted in oppositely-disposed sockets carried thereby, is a cross-bar 16, upon the center of which is mounted the wire-carrying shuttle 17. The shuttle comprises an elongated hollow member through which the 80 wire 18 passes and it is provided with clamping blocks 19 which prevent the wire from becoming disengaged from the shuttle. The supply of wire is carried on a suitable reel placed in the rear of the machine and the 85 wire is carried up between the two spaced frame parts and threaded into the shuttle, so that the end of the wire projects from the forward end of the shuttle. As the chains 14 are driven, the shuttle travels from 90 the upper forward edge of the bunch of shooks around the three sides of the bunch, to the lower forward edge of the bunch. The means for driving and controlling the movement of the chain will be hereinafter 95

100 set forth.

105

Arranged at the front of the frame is a vertically movable hollow frame or gate 21 which is engaged and guided by the grooved rollers 22 journaled on the frame 2. The 5 gate is movable upwardly and downwardly with periods of rest at the top and bottom of its reach, the movements and rests co-operating with other movements of the complete mechanism. Mounted in the upper 10 portion of the gate is a rotatable head 23, which is provided with means for gripping the end of the wire and drawing it down across the front face of the bunch of shooks when the gate is lowered. Attached to or 15 formed integral with the head is a sprocket 24 which is engaged by an endless chain 25 running over sprockets 26 disposed at the four corners of the frame. Movement of the chain causes rotation of the head and by 20 stopping the rotation of the head while the chain is being driven, the gate is raised or lowered. Meshing with the chain 25 is a driving sprocket 27 which is rotated in opposite directions in time with the operation of the machine, causing the raising and lowering of the gate and the operation of the 25 head at the proper times.

Formed on the rotatable head is a jaw or projection 28 which co-operates with a 10 spring-pressed jaw 29 rotatably mounted on the head. Secured to the spring-pressed jaw 29 is an arm 31 which is arranged to contact with a latch 32 mounted on the gate 21. When the sprocket 27 is rotated in a direction to move the chain 25 upwardly at the 15 sprocket, the chain is moved relatively to the gate and causes a rotation of the head in a clockwise direction (Fig. 6), bringing the arm 31 into contact with the latch 32. This stops the rotative movement of the 20 jaw 29, while the head continues to rotate, causing the jaws 28-29 to be opened. A stop 33 on the head then contacts with the arm 31, stopping the rotation of the head, 25 so that further movement of the sprocket 27 causes the gate to be raised, the position of the head during the upward movement of the gate being shown in Fig. 6.

Before the gate reaches its upper position, the shuttle 17 has been moved to its 50 position above the bunch of shooks as shown in dotted lines in Fig. 1, and the end of the wire 18 projects from the shuttle and lies in the path of the open jaws 28-29, so that when the gate reaches its upper position, the end of the wire 18 lies between the 55 jaws. The direction of rotation of the sprocket 27 is then reversed, and due to the pressure of the spring co-operating with jaw 60 29, the head is rotated for a short distance in a counter-clockwise direction (Fig. 7), bringing the jaw 28 against jaw 29 and clamping the end of the wire. The head is then prevented from rotating farther by a 65 spring-pressed stop 34 mounted on the gate

and engaging in a depression 35 in the periphery of the head. The stop and the depression have sloping sides, so that an increase in turning force on the head forces the stop out of engagement. 70

The head is provided with a sector-shaped slot 36 extending from the periphery to the center, and the slot is so disposed that its opening occurs at the lower part of the head, as the head moves downward. The upper 75 cross bar of the gate is open below the center of the head, so that the slot opens into the space within the gate. Before the gate reaches its lower position, the shuttle has traveled to a position below and in front of 80 the lower forward edge of the bunch of shooks, so that as the gate descends, the head passes down over the wire, seating the wire at the base of the slot. The gate having reached its lowermost position, is halted, 85 but the sprocket 27 continues to rotate, turning the head in a counter-clockwise direction (Fig. 7) for several turns. The spring latch 32 has an inclined upper face, so that the arm 31 in moving around, pushes the 90 latch 32 back at each revolution. This rotation of the head twists the ends of the wires together, firmly securing them and binding the bunch of shooks.

After turning in a counter-clockwise direction for a sufficient number of turns to tightly twist the ends of the wires, the head is rotated for a short distance in the opposite direction, to cut the wire. Formed on the opposite end of the jaw 29 is a knife 37 and when the direction of rotation of the head is reversed, the arm 31 contacts with the latch 32, halting its movement, and the further movement of the head brings the slot under the knife and the wire is cut. This finishes 100 one cycle of operations of the machine, and it is automatically stopped to permit the bound package to be removed and another package to be inserted, after which the 105 machine is again set in operation. 110

Journalized in the frame of the machine is the drive shaft 38 which is connected to any desirable prime mover. Secured to the drive shaft is a gear 39 which meshes with a gear 41 mounted for rotation on the shaft 58. 115 Loosely mounted on the shaft 58 adjacent the gear 41 is a gear 42 from which the chains are driven. The sprockets 12 which drive the chains 14 are secured to the ends of shafts 43-44 which are driven from the 120 shaft 48, through the sprockets 45-46 and the chains 47. The sprockets 12 are spaced apart and are secured to the adjacent ends of the shafts 43-44, so that an open space is provided between the sprockets to permit the 125 shuttle to pass. The shaft 48 is driven from the gear 42 through the gears 51, 52 and the shaft 53. In the operation of the machine the shuttle stops in two positions, one its upper position, which occurs above the upper 130

front edge of the bunch of shooks and two, its lower position, which occurs below the lower front edge of the bunch, and in moving from one position to the other it travels 5 around three sides of the bunch. Means are provided for halting the movement of the chains when the shuttle reaches either of these two stations and these means preferably coöperate with the gate-moving means, 10 so that the chains and gate move alternately.

Means are also provided for giving the vertically movable gate an intermittent motion, stopping it at the top and bottom and also for producing the desired movement of 15 the head. Secured to the shaft 58 and arranged adjacent the gear 41 is a gear wheel 59 which is adapted to be connected to the gear 41, so that they rotate together at certain portions of their revolutions. Carried 20 by the gear wheel 59 is a clutch member, comprising in this instance, an expanding band 62, which is disposed within the flange 61 of the gear 41, so that when the band is expanded the gear wheel 59 is clamped to 25 the gear 41. The gear 42 is similarly provided with an expanding band 63 which is disposed within the flange 64 on the opposite side of the gear 41, so that when the band is expanded, the gear 42 is clamped to 30 gear 41. The bands may be expanded in any suitable manner, such as by rotation of the cam 65. The cam 65 in the band 62 is provided with an operating lever 66 and the cam in band 63 is provided with an operating lever 67. The levers are arranged to 35 normally expand the bands, and means are provided for engaging the levers to move them to contract the bands. The gear wheel is provided adjacent the end of the lever 66 40 with a projection 96 to which the lever is connected by a spring 97 which normally presses the lever away from the projection, in which position of the lever the band 62 is expanded.

45 The gear wheel 59 is provided with an internal segmental gear 68 and a segmental gear 69 of lesser radius having exterior teeth, the gears being disposed so that they are brought into action successively. The 50 internal gear 68 covers an arc of approximately 180° and the external gear 69 an arc of less than 180° , the end of one gear being preferably angularly spaced from the beginning of the other gear. Secured to a shaft 55 71 and arranged within the gear wheel is a pinion 72 adapted to mesh successively with the internal and external segmental gears. The sprocket 27 which drives the chain 25 on the gate is secured to shaft 71, so that as 60 the gear wheel is rotated, the sprocket is rotated intermittently in opposite directions. The expanding band 62 is operated twice in each revolution of the gear wheel to release the gear wheel from the driving gear 41 so 65 that two periods of rest of the sprocket 27 are

provided for each revolution of the gear wheel. Arranged adjacent the gear wheel and in position to be engaged by the lever 67 are latches 73—74, each having a seat 75 adapted to be engaged by the lever. The 70 lever moves into the seat and against the shoulder 76 and its motion is arrested, and the further movement of the gear wheel causes a movement of the lever with respect to the gear wheel, turning the cam 65 and 75 contracting the band 62. This further movement of the gear wheel also compresses the spring 97 and causes the projection 66 to enter the seat in the latch, thereby holding the lever against movement in either direction and stopping rotation of the gear wheel. When it is desired to start the gear wheel again, the latch is disengaged from the lever, the spring forces the lever around, moving the cam and expanding the band. The 80 latches 73—74 are arranged so that they operate to stop rotation of the sprocket 27 when the gate has been raised to its upper position and also immediately after the wire 85 has been cut.

90 The latch 73 which operates to stop the rotation of the gear wheel after the wire has been cut is subsequently released by the handle 94. When the latch 73 is released, the gate rises to its upper position, where 95 it is halted by engagement of the lever 66 with the latch 74. Means are also provided whereby the arrival of the gate at its upper position releases the lever 67 controlling the band 63, so that the chain driving gear 42 100 is rotated to move the shuttle from its upper to its lower position. Arranged to engage the lever 67 is a latch 98, pivoted to the frame and operatively connected with a cam 99 secured to the gear wheel 59. The cam 105 is so positioned that when the gear wheel 59 reaches the position which corresponds to the upper position of the gate, that the latch 98 is raised. The gear 42 then rotates until the shuttle has moved to its lower position, 110 when the lever 67 engages the latch 102, contracting the band 63 and releasing the gear 42 from the drive gear 41. The latch 74 is operatively connected with a cam 103 secured to the gear 42 and this cam is so 115 placed that when the shuttle reaches its lower position, the latch 74 is operated to release the lever 66 and the band 62 is expanded, causing gear wheel 59 to rotate until the lever 66 is engaged by the latch 73, at which 120 time, the wire has been twisted and cut.

125 Means are provided for alining the stack of shooks and for compressing them during the binding operation. Slidably arranged in the frame at opposite sides thereof are two pairs of horizontal, longitudinally disposed rods 107—108, each pair of which carries a vertical bar 109 which is disposed behind the bunch of shooks. The vertical bars are provided with screw-threaded sockets 130

through which screw-threaded portions of the rods extend, so that rotation of the rods changes the setting of the vertical bars. In order that this setting may be readily accomplished, I provide each rod with a sprocket 111 and connect the sprockets with a chain 112. Pivoted to the frame and engaging each rod is a bell crank lever 113 which is connected at its other end to a rod 114, which is in turn connected to the lever 115. The lever 115 is provided with a roller 116 on its end which engages the cam 117 secured to the shaft 58, so that as the shaft rotates, the bars 109 are moved forward 15 against the stack of shooks, forcing them into alinement. Secured to shaft 58 is a second cam 118, with which co-operates a lever 119 pivoted to the frame. Arranged at the upper part of the frame and to one 20 side of the open center thereof, is a lever 121 to which the lever 119 is connected by the rod 122. Adjustably secured to the free end of the lever 121 is a presser foot 123, which, when the lever is depressed, bears 25 against and compresses the stack of shooks. The cams 117 and 118 are so disposed with relation to each other that the shook alining means is first brought into operation to straighten the stack of shooks and to shift 30 the stack to proper position, after which the presser foot is brought into operation. The cam 118 is of such dimensions that pressure on the stack is maintained until after the wire binding is completed.

35 The operation of the machine is as follows:

In the beginning, the shuttle 17 is at its upper station, the gate 21 is lowered, the head 23 is in the position shown in Fig. 6, 40 the lever 66 is in engagement with the latch 73, and lever 67 is in engagement with latch 98. The bunch of shooks is then placed on the machine and the handle 94 is moved to trip the latch 73, causing the gear wheel 59 45 to rotate (pinion 72 being in mesh with gear 69), and rotate the sprocket 27 in a clockwise direction, raising the gate to its top position. At this point lever 66 engages latch 74, stopping the gear wheel with the pinion 50 out of mesh with gear 69 and causing the head to rotate slightly to grip the end of the wire projecting from the shuttle. Latch 98 is then raised, causing a movement of the chains, to draw the wire tightly around the 55 three sides of the bunch, and then the shuttle is stopped by engagement of lever 67 with latch 102. Latch 74 is then tripped and gear wheel 59 is again rotated, causing the gate to lower due to the engagement of pinion 60 72 with gear 68. When the gate reaches its lower position, the wire enters the groove in the head and then the head is rotated several times, tightly twisting the wire. The gear 68 then moves out of engagement with the 65 pinion 72 and gear 69 moves into engage-

ment, giving the head a short rotation in the opposite direction to cut the wire and then the lever 65 seats in the latch 73. At the same time the latch 102 is operated by the cam 99 and the shuttle moves back to and is 70 stopped in its original position. The bound bunch of shooks is removed and the machine is in position to receive another bunch of shooks.

I claim:

1. In a wire binding machine, a support for the article to be bound, means for passing the wire around three sides of the article, a reciprocating gate for drawing the wire across the fourth side of the article and 80 means on the gate for cutting the wire.

2. In a wire binding machine, a support for the article to be bound, means for passing the wire around three sides of the article, a gate arranged to reciprocate across 85 the fourth side of the article, and means on the gate for gripping and twisting the end of the wire.

3. In a wire binding machine, a support for the article to be bound, a wire carrying 90 shuttle movable from a position above the article, around the article, to a position below the article, a gate arranged in front of the article, means on the gate for gripping the end of the wire at its upper position 95 and means for moving the gate to bring the end of the wire to the lower position.

4. In a wire binding machine, a support for the article to be bound, a wire carrying 100 shuttle movable from a position above the article, around the article to a position below the article, a gate arranged in front of the article, means on the gate for gripping the end of the wire at its upper position, 105 means for lowering the gate to bring the end of the wire to the lower position, and means on the gate for twisting the ends of the wire together.

5. In a wire binding machine, a support for the article to be bound, a wire carrying 110 shuttle movable from a position above the article, around the article, to a position below the article, a gate arranged to reciprocate in front of the article, means on the gate for gripping the end of the wire at its upper position, means for lowering the gate to bring the end of the wire to said lower position, and rotatable means on said gate 115 adapted to engage the wire which has been carried around the article, rotation of said means serving to twist the end of the wire and the engaged portion of the wire together.

6. In a wire binding machine, a support for the article to be bound, a wire carrying 120 shuttle movable from a position above the article, around the article, to a position below the article, a gate arranged to reciprocate in front of the article, means on the gate for gripping the end of the wire at its 125

upper position, means for lowering the gate to bring the end of the wire to said lower position, and rotatable means on said gate adapted to engage the wire which has been 5 carried around the article, rotation of said means serving to twist the end of the wire and the engaged portion of the wire together, and means coöperating with said rotatable means for cutting the wire.

10 7. In a wire binding machine, a support for the article to be bound, a wire carrying shuttle movable from a position above the article, around the article, to a position below the article, a gate arranged to reciprocate in front of the article, a rotatable head on said gate, means on the head for clamping the end of the wire in its upper position, means for lowering the gate to draw the wire across the side of the article and 15 bring the head into engagement with the other portion of the wire at its lower position, means for rotating said head in one direction to twist the adjacent parts of said wire together, and means for subsequently 20 rotating the head in the opposite direction, whereby the wire is cut.

8. In a wire binding machine, a support for the article to be bound, means for guiding a wire from a position above the article, 25 around the article to a position below the article and back to its upper position, and means coöperating with said wire guiding means for gripping the end of the wire and carrying the end from the upper position 30 across the article to the lower position in close relation to the other portion of the wire, and means for twisting together the two parts of the wire and cutting the wire.

9. In a wire binding machine, a frame including a support for the article to be bound, an endless chain extending around three sides of the article, a wire guiding shuttle carried by said chain, means for driving said chain, and means for stopping the motion 45 of the chain at predetermined points.

10. In a wire binding machine, a frame including a support for the article to be bound, an endless chain extending around three sides of the article, a wire guiding shuttle carried by said chain, means for driving said chain, and means for stopping the chain when the shuttle reaches its upper 50 forward position and its lower forward position.

11. In a wire binding machine, a frame including a support for the article to be bound, an endless chain extending around three sides of the article, a wire guiding shuttle carried by said chain, means for driving said chain, a clutch between said chain and driving means, and means for disengaging said clutch.

12. In a wire binding machine, a support for the article to be bound, means for passing a wire partly around the article, a verti-

cally reciprocating gate for drawing the wire around the remaining part of the article, means for raising and lowering said gate, means operative by the movement of the gate into its upper position for throwing 70 the wire passing means into operation and throwing the gate moving means out of operation.

13. In a wire binding machine, a frame including supports for the article to be bound, a pair of parallel transversely spaced endless chains extending around three sides of the article and a wire guiding shuttle arranged between and carried by said chains.

14. In a wire binding machine, a frame 80 comprising two frame parts spaced apart transversely, a support on each frame part for the article to be bound, an endless chain arranged on each frame part and extending around three sides of the article, said chains 85 being parallel, a wire shuttle arranged between and connecting said chains, and means for simultaneously driving said chains.

15. In a wire binding machine, a frame including supports for the article to be bound, a pair of parallel transversely spaced endless chains extending around three sides of the article, sprockets for said chain and an adjustable cross head carrying some of 90 said sprockets.

16. In a wire binding machine, a support for the article to be bound, a gate movable vertically across the face of the article means for moving said gate in opposite directions and means for disconnecting the gate from 100 the driving means at the end of its upward movement.

17. In a wire binding machine, a gate, an endless chain arranged on said gate, means for driving said chain, and means on the 105 gate for stopping the movement of the chain, whereby the driving means moves the gate.

18. In a wire binding machine, a gate, an endless chain on said gate, a driving sprocket engaging said chain, a sprocket on 110 said gate over which the chain passes, means for driving the sprocket whereby the chain is moved relatively to the gate, and means for stopping the rotation of the sprocket on the gate, whereby the driving 115 sprocket produces a movement of the gate.

19. In a wire binding machine, a gate, an endless chain on said gate, a driving sprocket engaging said chain, means for controlling the movement of the chain with respect to 120 the gate and means for reversing the direction of rotation of said sprocket.

20. In a wire binding machine, a gate, an endless chain mounted for movement on said gate, a rotatable head carried by said gate, 125 a sprocket on said head over which said chain passes, a driving sprocket, and means for controlling the rotation of said head.

21. In a wire binding machine, a gate, an endless chain mounted for movement on said 130

gate, a rotatable head carried by said gate, a sprocket on said head over which said chain passes, means for controlling the rotation of said head, a driving sprocket and 5 means for intermittently rotating the driving sprocket in opposite directions.

22. In a wire binding machine, a gate, an endless chain mounted for movement on said gate, a rotatable head on said gate, a sprocket 10 on said head engaging said chain, means for controlling the rotation of said head, a driving sprocket engaging said chain, means for intermittently driving the driving sprocket in opposite directions, and means for stopping the movement of the driving sprocket 15 at predetermined times during the operation of the machine.

23. In a wire binding machine, a gate, an endless chain mounted for movement on said 20 gate, a rotatable head on said gate, a sprocket on said head engaging said chain, an arm on said head, a stop on the gate arranged to be engaged by said arm and a driving sprocket engaging said chain.

24. In a wire binding machine, a gate, a rotatable head carried by said gate, means for moving said gate and rotating said head, and means on said head adapted to grip the end of the wire.

25. In a wire binding machine, a gate, a rotatable head carried by said gate, means for moving said gate and rotating said head, a fixed jaw on said head, a movable jaw pivoted on said head, and means for rotating said head to produce a relative movement of said jaws.

26. In a wire binding machine, a vertically movable gate, an endless chain mounted for movement on said gate, a rotatable head 40 on said gate, a sprocket on said head engaging said chain, means for retarding the rotation of said head, and a driving sprocket engaging said chain, rotation of the driving sprocket serving to lower said gate and then 45 rotate said head.

27. In a wire binding machine, a vertically movable gate, an endless chain mounted for movement on said gate, a rotatable head on said gate, a sprocket on said head engaging said chain, a driving sprocket engaging the chain, means for rotating the driving sprocket in one direction to first 50 lower the gate, then rotate the head in one direction and then reverse the direction of 55 rotation of the head.

28. In a wire binding machine, a vertically movable gate, an endless chain mounted for movement on said gate, means on the gate for controlling the movement of the 60 chain with respect to the gate, a driving sprocket engaging said chain, a driving shaft, a clutch between the driving sprocket and driving shaft, and means for releasing said clutch when the gate reaches a predetermined position.

29. In a wire binding machine, a reciprocating element, reciprocating driving means connected to said element, a drive shaft, a clutch between said drive shaft and said reciprocating driving means, and means 70 operative in time with the rotation of said driving means for operating said clutch.

30. In a wire binding machine, a vertically movable gate, an endless chain carried by said gate, means on said gate for controlling the movement of said chain, a driving sprocket engaging said chain, a pinion associated with said sprocket and a gear wheel having internal and external gears successively engaging said pinion, whereby 75 said sprocket is alternately rotated in opposite directions.

31. In a wire binding machine, a vertically movable gate, an endless chain carried by said gate, means on said gate for controlling the movement of said chain, a driving sprocket engaging said chain, a pinion associated with said sprocket and a gear wheel having internal and external gears successively engaging said pinion, whereby 80 said sprocket is alternately rotated in opposite directions, a drive shaft, a clutch between said drive shaft and gear wheel, and means operated by the rotation of the gear wheel for releasing said clutch.

32. In a wire binding machine, a vertically movable gate, an endless chain carried by said gate, means on the gate for controlling the movement of the chain, a driving sprocket engaging said chain, a drive 100 shaft, a clutch and rotation reversing means arranged between the sprocket and the drive shaft whereby the sprocket is rotated in opposite directions, and means operative when the gate reaches its upper position for 105 disengaging said clutch.

33. In a wire binding machine, a vertically movable gate, an endless chain carried by said gate, means on the gate for controlling the movement of the chain, a driving sprocket engaging said chain, a drive shaft, a clutch and rotation reversing means arranged between the sprocket and the drive shaft whereby the sprocket is rotated in opposite directions, and means operative 110 after the gate has reached its lower position for disengaging said clutch.

34. In a wire binding machine, a vertically movable wire drawing element movable from a lower to an upper position and 120 vice versa, a driving shaft, driving means connected to said element, a clutch and motion reversing means arranged between said element and drive shaft, and means for disengaging said clutch to halt the movement 125 of the element when it reaches its upper and lower positions.

35. In a wire binding machine, a frame including a support for the article to be bound, a gate movable vertically across the 130

- face of the article, means on the gate for gripping the end of the wire, an endless chain on said gate, a sprocket engaging said chain, a pinion connected to said sprocket, 5 a gear wheel having internal and external gears adapted to successively engage said pinion and rotate it in opposite directions, a drive shaft, a clutch carried by said gear wheel and adapted to engage said drive 10 shaft, a clutch lever on said gear wheel and a latch adapted to engage said lever to release the clutch and stop said gear wheel.
36. In a wire binding machine, a gate adapted to be reciprocated, a rotatable head 15 on said gate, a slot in said head adapted to receive the wire, a clamp on said head adapted to clamp the end of the wire and means for rotating said head whereby the wires are twisted.
- 20 37. In a wire binding machine, a gate adapted to be reciprocated, a rotatable head on said gate, a radial slot in said head adapted to straddle the wire, a clamp on said head on the opposite side of the center from 25 said slot adapted to grip the end of the wire and means for rotating said head.
38. In a wire binding machine, a gate adapted to be reciprocated, a rotatable head 30 on said gate, a slot in said head adapted to straddle the wire, a clamp on said head adapted to grip the end of the wire, a knife on said head for cutting the wire, means for 35 rotating the head in one direction whereby the wires are twisted together, an arm engaging said knife and a stop adapted to be engaged by said arm on the reverse rotation of said head.
39. In a wire binding machine, a gate 40 adapted to be reciprocated, a rotatable head on said gate, a slot in said head arranged to straddle the wire, a projection on said head, a spring pressed jaw coöoperating with said projection, an extension on said jaw adapted to be moved over said slot to cut 45 the wire extending therethrough, an arm secured to said jaw and a latch on said gate arranged to be engaged by said arm.
40. In a wire binding machine, a frame 50 including supports for the article to be bound, a wire guiding shuttle movable from a position above the article around the article to a position below the article, a gate movable across the face of the article, a rotatable head on said gate, means on the head 55 for gripping the end of the wire at its upper position, a slot in said head adapted to straddle the wire in its lower position and means for first moving the gate downward to seat said wire in the slot and then rotating said head.
41. In a wire binding machine, a frame 60 including supports for the article to be bound, a presser foot arranged above the article, a driven shaft, means connecting said presser foot and shaft for lowering the

presser foot to compress the article, means for passing a wire around the compressed article and means for twisting the ends of the wire together.

42. In a wire binding machine, a frame 70 including supports for the article to be bound, a presser foot arranged above the article, a driving shaft, a driven shaft, a clutch arranged between said shafts, a cam on said driven shaft and means connecting 75 the cam and the presser foot.

43. In a wire binding machine, a frame including a support for the article to be bound, vertical bars arranged behind the article and means for moving said bars longitudinally of the machine to properly position the article.

44. In a wire binding machine, a frame including a support for the article to be bound, vertical bars arranged behind the 85 article, longitudinally reciprocable rods on which said bars are mounted, a driven shaft and means on the driven shaft for reciprocating said rods.

45. In a wire binding machine, a frame 90 including a support for the article to be bound, vertical bars arranged behind the article, screw threaded sockets on said bars, screw threaded rods extending through said sockets, means for simultaneously rotating 95 said rods whereby the bars are moved to adjusted positions and means for reciprocating said rods to move the bars toward and away from the article.

46. In a wire binding machine, a support 100 for the article to be bound, an endless chain extending around three sides of the article, a wire guiding shuttle carried by said chain, a gate movable across the fourth side of the article, means for moving said gate, means 105 for driving said chain, a drive shaft, a clutch between the drive shaft and chain-driving means, a clutch between the drive shaft and gate-moving means, and means for alternately operating said clutches.

47. In a wire binding machine, a support 110 for the article to be bound, an endless chain extending around three sides of the article, a wire guiding shuttle carried by said chain, a gate movable across the fourth side of the 115 article, means for moving said gate, means for driving said chain, a drive shaft, a clutch between the drive shaft and chain driving means, a clutch between the drive shaft and gate moving means, means operative by the 120 movement of the gate moving means for operating the chain driving clutch and means for operating the gate moving clutch.

48. In a wire binding machine, a support 125 for the article to be bound, an endless chain extending around three sides of the article, a wire guiding shuttle carried by said chain, a gate moving across the fourth side of the article, means for moving said gate, means for driving said chain, a drive shaft, a clutch 130

between the drive shaft and chain driving means, a clutch between the drive shaft and gate moving means, means operative by the movement of the chain driving means for 5 operating the gate moving clutch, and means for operating the chain driving clutch.

49. In a wire binding machine, a support for the article to be bound, an endless chain extending around three sides of the article, 10 a wire guiding shuttle carried by said chain, a gate moving across the fourth side of the article, means for moving said gate, means for driving said chain, a drive shaft, a clutch between the drive shaft and chain driving means, a clutch between the drive shaft and gate moving means, means operative by the movement of the chain driving means for 15 operating the gate moving clutch, and means operative by the movement of the gate moving means for operating the chain driving clutch.

50. In a wire binding machine, a support for the article to be bound, wire guiding means movable from an upper position to a 25 lower position and back again, wire drawing means movable from a lower position to an upper position and back again, and mechanism for moving the wire drawing means from the lower to the upper position, then 30 moving the wire guiding means from the upper to the lower position and then moving the wire drawing means from the upper to the lower position.

51. In a wire binding machine, a support 35 for the article to be bound, wire guiding means movable from an upper position to a

lower position and back again, wire drawing means movable from a lower position to an upper position and back again, means for 40 moving said guiding means and drawing means, and mechanism operated by the movement of the drawing means into its upper position for causing the guiding means to be moved from the upper to the lower position, and means operated by the movement of the guiding means to its lower position for causing the drawing means to be moved to its lower position.

52. In a wire binding machine, a support for the article to be bound, wire guiding 50 means movable from an upper position to a lower position and back again, wire drawing means movable from a lower position to an upper position and back again, a drive shaft, means arranged to connect the drive 55 shaft and the drawing means, means arranged to connect the drive shaft and the guiding means, means operative by the movement of the drawing means from its lower to upper position for connecting the 60 guiding means drive to the drive shaft, and means operative by the movement of the guiding means from its upper position to the lower position for connecting the drawing means drive to the drive shaft.

In testimony whereof I have hereunto set my hand at San Francisco, California, this 18th day of December, 1917.

ROBERT J. SMIRLE.

In presence of—
H. G. PROST.
